Garrison Smith & Henry Brown of Philadelphia, Pa.

Assignors to

Cox, Whitteman & Cox, of same place.

Letters Patent No. 1286. Dated July 3, 1860.

The schedule referred to in these Letters Patent and making part of the same.

To all whom it may concern:

Be it known that we, Garrison Smith & Henry Brown, both of the City of Philadelphia, State of Pennsylvania, have invented or produced a new and original design for the plates of cooking stove, termed the "Oral", and we do hereby declare the accompanying drawing and the following explanation of the same, to be a full clear and exact illustration and description of the said design the drawing representing a view of the stove in perspective.

A is one of the side plates of the stove having a large door a, and a smaller door b. — B. is the front plate with an upper door d, and two lower doors e.

The plates are edged with plain mouldings and the doors a, b and e, have also plain mouldings on the edge, and the scroll and foliated ornaments represented in the drawings. The door d, having ornaments of a similar character.

We claim the ornamental figures and forms on the front and side plates and doors as represented in and by the accompanying drawing the whole forming an ornamental design for plates of a cooking stove.

In testimony whereof, we have signed our names to this specification, in the presence of two subscribing witnesses.
